UNITED STATES PATENT OFFICE

2,312,861

REFRIGERATING MACHINE

Leonard W. Atchison, Schenectady, N. Y., assignor
to General Electric Company, a corporation of
New York

Application July 1, 1941, Serial No. 400,588

5 Claims. (Cl. 62—116)

My invention relates to refrigerating machines, and more particularly to such machines having cooling units arranged to provide a plurality of zones operating at different temperatures.

Refrigerating machines, and particularly household refrigerators, are commonly provided with evaporators which are designed to provide adequate surface to cool the air in the cabinet and also a low temperature zone in which water, desserts, and the like may be frozen. Some evaporators for this purpose have been designed with one evaporator arranged within the other. The freezing zone is defined and cooled by the inner evaporator and a higher temperature cooling zone is refrigerated by the outer evaporator. This arrangement permits the inner evaporator to be operated at a relatively low temperature and the outer evaporator at a relatively high temperature. If the inner evaporator is completely or substantially enclosed the air in the food compartment will not circulate through the freezing zone where a substantial quantity of moisture would be removed from the air, thereby minimizing the accumulation of frost on the walls of the inner evaporator and thereby increasing the time between defrosting periods. The rate of dehydration of food in the refrigerator cabinet may be minimized since the cabinet evaporator may be maintained at temperatures above freezing, in which case no frost will accumulate on the warmer outer evaporator.

Accordingly, it is an object of my invention to provide a refrigerating machine having an improved cooling unit for establishing a plurality of cooling zones in a refrigerator cabinet.

Another object of my invention is to provide a refrigerating machine including an evaporator having a plurality of sections and an improved arrangement for maintaining each of said sections at a different temperature.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a front elevation of the upper portion of a household refrigerator machine containing a cooling unit embodying the principles of my invention; Fig. 2 is a sectional view taken along the line 2—2 of Fig. 1 illustrating the arrangement of the cooling unit disclosed in

Fig. 1; and Fig. 3 illustrates a detail of a modification of the arrangement shown in Fig. 1.

I have shown a refrigerator cabinet of the domestic type including a food storage compartment 10 normally closed by a door (not shown) and a cooling unit 11 arranged within the compartment 10. A suitable refrigerant liquefying and circulating means is provided but inasmuch as the details thereof form no part of the present invention and conventional apparatus may be employed, it is believed unnecessary to illustrate the details thereof. It will be understood that a condensing unit will be provided for compressing gaseous refrigerant withdrawn from the cooling unit or refrigerant evaporator 11, cooling and liquefying the refrigerant and returning the liquid refrigerant to the cooling unit through a receiver or float valve chamber 12. When a predetermined quantity of liquid refrigerant has collected in the chamber 12, a float therein rises and the liquid refrigerant flows through conduits 13 and 14 to the inner evaporator 15. The liquid refrigerant within the evaporator 15 is vaporized by the absorption of heat from the air within the freezing zone 16, defined by the inner evaporator 15, and from articles placed within the freezing zone, and the vaporized refrigerant is withdrawn through a suction line 17 and returned to the condensing unit. There is provided control mechanism including a thermostatic element 18 secured adjacent the outer portion of the evaporator 15, the motor within the condensing unit being started and stopped by the control mechanism in response to the temperature of the thermostatic element 18. The refrigerating machine thereby maintains the evaporator 15 within a predetermined range of temperature.

The evaporator or cooling element 15 in the illustrated form of my invention is constructed of two sheets of metal shaped and arranged to provide adequate surface for cooling the air adjacent the surfaces thereof and a plurality of surfaces for supporting freezing trays and the like. As best seen in Fig. 2, the evaporator 15 is made of inner and outer sheet metal portions 21 and 22, respectively, the outer portion 22 being corrugated to provide a plurality of depending refrigerant circulating passages or conduits 20, although both sheets 21 and 22 are provided with indentations to provide a header 19. Portions of the refrigerant passages are arranged in the freezing tray supporting surfaces so as to provide for the absorption of heat from the freezing trays and the like. The sheets are suitably joined together as by welding, for example, and then

turning over the marginal edges of the inner relatively flat sheet 21 over the marginal edges of the sheet 22. The assembled sheets are then bent to form side walls, a bottom wall, and a shelf, the bottom wall and the shelf providing lower and upper surfaces for supporting freezing trays and the like. A metal sheet 23 may be secured as by welding to the upper end of the side wall opposite the header and constitutes a side wall for an upper freezing chamber.

The evaporator 15 is designed to run at a relatively low temperature and provide within it a cold compartment or zone 16 for keeping frozen foods, freezing water, desserts, and the like. I have provided a shield 24 disposed between the evaporator 15 and that part of the food storage compartment 10 exterior to the evaporator 15. The shield preferably is arranged to provide a complete enclosure for the evaporator 15. As best seen in Fig. 2, in the form of my invention illustrated and described herein, the shield 24 is open at the front and rear, but the cooling unit is so disposed that the rear wall 25 of the refrigerator cabinet abuts the rear edges of the shield 24 and thereby provides a rear wall therefor. The shield is provided with inwardly directed flanges 26 at the front end thereof thereby closing the space between the shield 24 and the evaporator 15. In order to close the front end of the evaporator 15 there is provided a sheet metal door 27 which may be hinged to the flange 26, as indicated by the numeral 28.

In the form of my invention illustrated in the drawing the shield 24 is provided with refrigerant passages. In other words, the shield takes the form of a second evaporator thereby providing a cooling unit having one evaporator arranged within a second evaporator. The shield or evaporator 24 may be formed in a manner similar to the evaporator 15 in that a pair of sheet metal members 29 and 30 may be provided, the outer member 30 being provided with a series of horizontally disposed corrugations 40 connected together by vertical corrugations 41 to provide a series of refrigerant passages on each end of the sheet. The sheets may be suitably joined together to provide fluid-tight passages as by means of welding, brazing, or the like and then bent into a substantially U-shape. The outer evaporator may also be a piece of sheet metal with tubing soldered or brazed to it to provide a refrigerant conduit and the assembly then bent into a U-shape. Two sets of refrigerant passages are thus provided, one on each of the side walls of the shield, the sets being joined at the lower ends thereof by means of an interconnecting conduit 31. In order to supply refrigerant to the outer evaporator there are provided conduits 32 and 33 communicating with the conduits 13 and 14 as by means of a T-connection 34. Means is provided for withdrawing gaseous refrigerant from the outer evaporator in the form of a conduit or tube 35 communicating between the upper passage of the refrigerant conducting section remote from the liquid refrigerant supply conduit 33, and the upper portion of the header 19. The outer evaporator 24 may be suitably supported from the top wall of the compartment 10 by means of sheet metal brackets 36 suitably secured, as by welding, to the upper edge of the evaporator and to the top wall of the compartment. If desired, the brackets 36 may be integral with one or the other of the sheets 29 or 30.

In order to control the supply of liquid refrigerant to the outer evaporator I have provided

flow controlling means in the form of a solenoid operated valve 37 in the liquid refrigerant supply line to the outer evaporator. In order to control the solenoid valve I have provided means

5 responsive to or related to the compartment air temperature, as for example, a thermostatic device 38 connected in an electrical circuit including the coil 39 of the solenoid operated valve, the thermostat 38, and a suitable source of power.

10 In the form of my invention shown in the drawing the thermostatic device is suitably supported on a side wall of the food storage compartment 10, but it will be understood that any suitable disposition of the temperature responsive device may be employed. For example, the temperature responsive device could take the form of a thermostatic bulb containing an expansible liquid and arranged in contact with the shield or evaporator 24. Furthermore, it is entirely possible to provide 15 a mechanically operated valve in the place of the solenoid operated valve which will serve the functions heretofore described.

In normal operation of a refrigerator cabinet of the domestic type the food storage compartment will be adequately cooled by the inner evaporator 15. However, in case a heavy load is im-

25 posed on the main food compartment 10 so that the temperature of the box air tends to rise unduly, the refrigerant capacity of the outer evaporator or shield will be made available through operation of the solenoid valve in response to ac-

30 tion of the thermostatic device, allowing some of the liquid refrigerant from the float chamber 12 to flow through the conduit 32, valve 37 and con- 35 duct 33 into the fluid or refrigerant conveying passages in the shield. Thus, when additional refrigeration is required the whole outer shield, or parts of it according to the disposition of the refrigerant passages, can be made to serve as

40 an evaporator running at a somewhat higher temperature than the evaporator 15 to compensate for the greater load and augment the cooling capacity of the refrigeration apparatus.

Modifications will occur to those skilled in the 45 art. For example, the evaporator 15 and the shield 24 may be operated continually as evaporators, and the space between the evaporators 15 and 24 may be filled with suitable heat insulating material, thereby minimizing the transfer of heat 50 between the two evaporators. With such an arrangement the outer member 24 would serve as a shield for preventing the box air from circulating across the walls of the evaporator 15 but the evaporator function of the shield member 24 55 must be relied upon entirely to provide cooling for the food storage compartment 10.

While I have described what I at present consider the preferred embodiment of my invention, it will be obvious to those skilled in the art that various changes and modifications may be made without departing from my invention. For example, I may provide a restriction 42 in the conduit 14 as shown in Fig. 3, as a capillary tube, for example, for preventing excessive flow of liquid refrigerant to the evaporator 15. Such a restriction also insures a substantial flow of liquid refrigerant to the outer evaporator or shield 24 when the flow controlling means 37 is in the flow permitting position. I, therefore, aim in the appended claims to cover all such changes and modifications as fall within the true spirit of my invention.

What I claim as new and desire to secure by Letters Patent of the United States is:

1. In a refrigerating machine including a cabi-

net having a food storage compartment to be cooled and a refrigerant circulating system comprising a cooling unit arranged within said food compartment and refrigerant flow-controlling means for controlling the flow of liquid refrigerant to said unit, said cooling unit comprising two evaporators connected in parallel relationship in said system and arranged one within the other, means for supplying refrigerant to said inner one of said evaporators, said inner one of said evaporators being of the flooded type and having a header and a plurality of depending refrigerant circulating conduits, means for supplying refrigerant to the outer one of said evaporators, said outer one of said evaporators being of the dry type, flow controlling means arranged in said last mentioned supply means for controlling the flow of refrigerant to said outer evaporator, temperature responsive means for controlling said flow controlling means, and means for withdrawing the gaseous refrigerant from said evaporators.

2. In a refrigerating machine including a cabinet having a food storage compartment to be cooled and a refrigerant circulating system comprising a cooling unit arranged within said food storage compartment and refrigerant flow-controlling means for controlling the flow of liquid refrigerant to said unit, said cooling unit comprising two evaporators connected in parallel in said system and arranged one within the other, means for supplying refrigerant to the inner one of said evaporators, said inner one of said evaporators being of the flooded type, said supply means also being arranged for supplying refrigerant to the outer one of said evaporators, said outer one of said evaporators being of the dry type, means including a solenoid operated valve arranged in said last mentioned supply means for controlling the flow of refrigerant to said outer evaporator, means responsive to the compartment air temperature for controlling the operation of said valve, and means for withdrawing gaseous refrigerant from said evaporator.

3. In a refrigerating machine including a cabinet having a food storage compartment to be cooled and a refrigerant circulating system comprising a cooling unit arranged within said food storage compartment, said cooling unit having portions connected in parallel in said system and arranged one within the other in order to provide a freezing zone and a cooling zone, means for supplying refrigerant to the freezing portion of said cooling unit, said freezing portion being

of the flooded type, means for supplying refrigerant to the cooling portion of said evaporator, said cooling portion of said evaporator being of the dry type, flow controlling means arranged in said last mentioned supply means for controlling the flow of refrigerant to said cooling portion, temperature responsive means for controlling said flow controlling means, and means for withdrawing gaseous refrigerant from said portion.

4. In a refrigerating machine including a cabinet having a food storage compartment to be cooled and a refrigerant circulating system comprising a cooling unit arranged within said food storage compartment, means for supplying liquid refrigerant to said cooling unit, said cooling unit being of the flooded type, a shield member disposed about and spaced from said cooling unit and substantially enclosing said cooling unit, said shield member being provided with auxiliary refrigerant circulating passages, means connecting said passages in parallel circuit relationship with said cooling unit, flow controlling means arranged for controlling the flow of refrigerant to said auxiliary passages, temperature responsive means for controlling said flow controlling means whereby said auxiliary passages augment the cooling capacity of the cooling units, and means for withdrawing gaseous refrigerant from said cooling unit and said auxiliary passages.

5. In a refrigerating machine of the type comprising a cabinet provided with a food storage compartment to be cooled and a refrigerant circulating system including a cooling unit in said compartment and refrigerant flow-controlling means for controlling the flow of liquid refrigerant to said unit, said cooling unit comprising two evaporators connected in parallel in said system and arranged one within the other, the inner evaporator being of the flooded type and having a header and a plurality of depending refrigerant circulating conduits, means including a restrictor for conducting refrigerant from said flow-controlling means to said inner evaporator, the outer evaporator being of the dry type, means for conducting liquid refrigerant from said flow controlling means to said outer evaporator, additional flow-controlling means disposed in the last-mentioned refrigerant conducting means between said first-mentioned flow-controlling means and said outer evaporator, and means for withdrawing gaseous refrigerant from said evaporators.

LEONARD W. ATCHISON.
